UNITED STATES PATENT OFFICE.

FRIEDRICH DAVID, OF BROOKLYN, NEW YORK, ASSIGNOR TO ENTERPRISE ELECTRIC NOVELTY CO., OF NEW YORK, N. Y., A CORPORATION.

FLASH-LIGHT LAMP.

1,213,754.

Specification of Letters Patent.

Patented Jan. 23, 1917.

Application filed September 18, 1916. Serial No. 119,887.

To all whom it may concern:

Be it known that I, FRIEDRICH DAVID, a citizen of Germany, and a resident of the borough of Brooklyn, city of New York, in the county of Kings and State of New York, have invented a certain new and useful Flash-Light Lamp, of which the following is a specification.

This invention relates to portable lamps which may be readily lighted, generally known as flashlight lamps.

The object is to provide means whereby the lamp may be readily lighted or extinguished when desired, and to provide means whereby the lamp will not be liable to accidental lighting.

The invention consists of a manually operative electric switch forming part of a removable cap for a casing, which casing in- 20 closes an electric battery and an electric lamp connected to the battery and to the casing.

The invention also consists of means for holding the switch in positions adapted for lighting or for extinguishing the lamp.

In the accompanying drawing: Figure 1 is a longitudinal section of the lamp, showing the switch in a position which causes an electric circuit to be closed for the purpose 30 of lighting the lamp. Fig. 2 is a transverse section approximately on the line II-II of Fig. 1. Fig. 3 is a longitudinal section approximately on the line III-III of Fig. 1. Fig. 4 is a sectional elevation, showing the 35 casing and removable cap, and the means for holding the switch in place. Fig. 5 is a perspective view of the cap when removed from the casing.

Mounted in a cylinder casing 1 is a reflector 2, having a central screw threaded aperture 3 in which is fitted an electric lamp 4. One contact 5 of the lamp is in electric communication with the reflector 2, the other contact 6 being adapted for making 45 electric contact with a pole 7 of an electric battery 8. The battery is covered by means of an insulating cylinder 9, the other pole 10 of the battery being located at the end of the insulating cylinder opposite to that in which the pole 7 is located.

Reflector 2 is electrically connected to one end of a conducting strip 11 on the interior of casing 1. The other end of strip 11 is connected to an electric conductor sleeve 12

having a screw thread 13 formed on its exterior.

When the battery has been placed in the casing, as shown in Fig. 1, the open end 14 of the casing is closed by means of a cap 15 which is provided with a screw thread 16 adapted for engagement with the screw thread 13 of sleeve 12. Two insulating disks 17 and 18 are secured to the interior of the cap by means of a rivet 19. A lever 20 is pivoted on a rivet 21 which passes through the two insulating disks and the wall 22 of the cap. The free end of lever 20 extends out through a slot 23 formed in the cylindrical part of the cap, and is bent to form a handle by means of which the lever can be moved back and forth in the slot. A plate 24 is secured to the insulating disk 18 by means of rivets 25, the rivets being insulated from the cap by means of the insulating disk 17. Plate 24 is provided with a spring arm 26 which is arranged so that lever 20 is moved into engagement therewith when moved to one end of the slot 23, as shown by full lines in Fig. 2. Plate 24 is also provided with a spring arm 27 which extends away from the insulating disk 18, across over the plate 24 and lever 20 and inward toward the disk 18 as shown in Fig. 5.

When the cap is screwed onto the sleeve 12, the spring arm 27 will be forced against the pole 7 of the electric battery 8, and will thereby be compressed, causing it to swing from the position shown in Fig. 5 to the position shown in Fig. 3, the in-turned end of the arm being then forced against the insulating disk 18, thereby serving to prevent contact of the arm with the lever 20. When the cap is thus screwed to place, it is held by means of a screw 28 which is passed through a hole 29 formed in the cap and screwed into the casing 1.

When the light is to be turned on, lever 20 is moved from the position shown by dotted lines in Fig. 2 to the position shown by full lines. Electric current will then pass from the battery 8 through the lamp 4, reflector 2, conducting strip 11, conductor sleeve 12, cap 15, rivet 21, lever 20, spring arm 26, plate 24, spring arm 27, back to the battery. Lever 20 will then be at the end of the slot 23 as shown in Fig. 4, and will be held in this position by means of the curvature 30 formed in the central part

of the slot. When the light is to be turned off, lever 20 will be moved to the other end of slot 23, during which movement the lever will be sprung away from its true line of 5 travel on its pivot 21, by passage through the curvature 30, so that the lever will be held in place at the end of the slot. Accordingly there will be no electric circuit through the battery until the lever 20 is 10 moved with force sufficient to overcome the resistance offered by the curvature 30 of the slot 23.

Having described my invention, what I claim is.

- 15 1. A portable lamp, comprising a cylindrical casing inclosing an electric battery; an electric lamp connected to the casing and to one pole of the battery; a rotatable removable cap having a screw thread adapted 20 for electrical engagement with a screw thread formed on said cylindrical casing; said cap having an insulated contact adapted to be forced against the other pole of said battery by means of said screw threads when said cap is rotated, said cap having a manually operative lever pivoted thereto and in electric connection therewith and adapted to be thrown into or out of engagement with said contact, whereby said 25 lamp may be alternately lighted or extinguished.
- 25 2. A portable lamp, comprising a cylindrical casing having an electric lamp mounted in one end thereof, one contact of 30 the lamp being electrically connected to the casing; the other end of the casing being open; an electric battery adapted to be placed in said open end of the casing in such a manner that one pole of the battery

can make contact with the other contact of 40 said lamp; a rotatable removable cap having a screw thread adapted for electrical engagement with a screw thread formed on said open end of the cylindrical casing; said cap having an insulated contact provided with a spring extension adapted to be forced against the other pole of said battery by means of said screw threads when said cap is rotated, said spring thereby serving to hold the battery against said 45 lamp; said cap having a manually operative lever pivoted thereto and in electric connection therewith and adapted to be thrown into or out of engagement with said contact, whereby said lamp may be alternately 50 lighted or extinguished.

3. A portable lamp, comprising a cylindrical casing inclosing an electrical battery; an electric lamp connected to the casing and to one pole of the battery; a rotatable removable cap having a screw thread adapted 60 for electrical engagement with a screw thread formed on said cylindrical casing; said cap having an insulated contact adapted to be forced against the other pole 65 of said battery by means of said screw threads when said cap is rotated; adjusting means for preventing rotating of said cap; said cap having a manually operative lever pivoted thereto and in electric connection 70 therewith and adapted to be thrown into or out of engagement with said contact, whereby said lamp may be alternately lighted or extinguished.

Signed at New York city in the county of 75 New York and State of New York this 12th day of September A. D. 1916.

FRIEDRICH DAVID.
